UNITED STATES PATENT OFFICE.

ANDERS H. NESHEIM, OF MILWAUKEE, WISCONSIN, ASSIGNOR TO FEDERAL STEEL SASH COMPANY, OF WAUKESHA, WISCONSIN, A CORPORATION OF WISCONSIN.

VENTILATING-SKYLIGHT-OPERATING DEVICE.

Application filed January 7, 1924. Serial No. 634,886.

This invention relates to closure operating devices and more particularly to a device for operating ventilating skylights, and has for one of its objects to provide a device of this character whereby the skylights of a building may be readily adjusted to compensate for atmospheric conditions, while at the same time providing the desired ventilation.

10 A further object of the invention is to provide a device adapted to control a pair of skylights disposed upon opposite sides of the roof of a building, which will permit of either or both of the said skylights being 15 opened fully, partially, or wholly closed.

A still further object of the invention is to provide a skylight operating mechanism in which one of the skylights is positively actuated at all times, while the other one is 20 connected to the said operating mechanism by means of a lost motion connection, whereby various relative adjustments of the two skylights may be obtained.

A still further object of the invention is 25 to provide a device of the class described which will be simple in construction, comparatively inexpensive to manufacture and install and more efficient in use than those which have been heretofore proposed.

30 With the above and other objects in view, which will appear as the description proceeds, the invention consists in the novel details of construction and combinations and arrangements of parts more fully hereinafter described and particularly pointed 35 out in the appended claims.

Referring to the accompanying drawings in which like numerals designate like parts in all the views:

40 Figure 1 is a cross sectional view through the upper portion of a building, such, for example as a factory building, which is provided with a pair of oppositely disposed skylights pivotally secured to the ridge of the roof and provided with an actuating mechanism constructed in accordance with the present invention;

Fig. 2 is a diagrammatic view showing the right hand skylight fully open, and 50 the left hand skylight fully closed;

Fig. 3 is a similar view, showing both skylights partially opened;

Fig. 4 is a similar view showing the left hand skylight fully opened and the right 55 hand one fully closed;

Fig. 5 is a side elevational view, partly broken away for the sake of clearance, of the actuating mechanism;

Fig. 6 is a front elevational view, partly broken away, of the parts shown in Fig. 5; 60 and,

Fig. 7 is a fragmentary detail view of one of the actuating arms or levers for the skylights.

Referring more particularly to the said 65 drawings, the numeral 10 indicates the upper portion of a building, such for example as a factory building of the well known metal construction, the ridge 11 of which has pivotally secured to it, as at 12 and 13, 70 the skylight members, 14 and 15, respectively. These said skylights may be of any suitable construction, inasmuch as they themselves constitute no part of the present invention, and they are adapted to be swung 75 to the various positions indicated by dotted lines in Fig. 1, by means of the actuating mechanism, which will now be described.

Referring more particularly to Figs. 1, 5 and 6, it will be seen that there is provided a vertical supporting member 16 of T or angle iron construction, to which is secured a pair of spaced angle members 17, which have secured to them a bracket or frame member 18, which supports the various moving parts of the operating device. The said bracket has journalled in it a longitudinally extending shaft 20, the parts being so designed, constructed and arranged that the said shaft would extend 90 longitudinally of the building and approximately on the center line thereof below the ridge 11.

The said shaft has rigidly secured to it a worm wheel 21, which meshes with a 95 worm 22, rigidly carried by a transverse stub shaft 23, which latter shaft rigidly carries a chain wheel or pulley 24, over which passes an operating chain 25. The said chain as it leaves one side of the wheel 24, passes 100 through a suitable chain guide 26, carried by an extension 27 of the bracket member 18, as will be clear from the drawings.

The shaft 20 also carries a pair of operating arms or levers, 30 and 31, the former of which is rigidly secured to the said shaft in any suitable manner, as by the pin 32, while the latter arm 31 is loosely mounted upon the said shaft and is provided with the oppositely disposed shoulders 33, see Fig. 110

6, which are adapted to be engaged by companion shoulders 34, formed upon collars 35, rigidly secured to the said shaft 20, in any suitable manner, as by the pins 36. The 5 shoulders or lugs 33 and the arms 31 and 34 of the collars 35 are of such arcuate dimensions as to permit of a predetermined amount of play or lost motion between the arm 31 and the shaft 20, so that the said shaft may 10 be moved through a predetermined arc without transmitting motion to the arm 31, for a purpose which will appear more fully below.

The extreme end of the arm 30 has pivotally secured to it, as at 40, a connecting rod or link 41, the other end of which is pivotally connected as at 42 to the skylight member 14. In like manner the extreme end of the arm or lever 31 has pivotally secured 20 to it as at 43, one end of a connecting rod or link 44, the other end of which is pivotally connected as at 45 to the skylight member 15.

The operation of the device, is as follows. 25 Assuming the parts to be in the full line position shown in Fig. 1, wherein both skylight members, 14 and 15, are shown closed, if the right hand side of the chain 25, as seen in Fig. 6, is pulled downwardly, thereby 30 rotating the chain wheel 24 in a clockwise direction, as viewed in the said figure, the motion will be transmitted through the shaft 23 and worm 22 to the worm wheel 21, which will be moved in a counter-clockwise direction, as viewed in Figs. 1 and 5. This movement of the wheel 21 may be transmitted through the shaft 20 to the arm 30, the outer end of which will move upwardly in a 35 counter-clockwise direction to successively assume the positions indicated in dotted lines in Fig. 1 and designated respectively by the reference characters 30' and 30''. This movement of the said arm will be transmitted through connecting link 41 to the skylight 14, which will likewise successively 40 assume the dotted line positions indicated in the said figure.

During such motion of the shaft, no movement has been transmitted to the arm 31, 50 due to the fact that the parts have been so assembled that the shoulders 34 of the collars 35 have not yet engaged the shoulders 33 of the said arm. However, when the uppermost position of the skylight 14 is 55 reached, the said shoulders will engage so that any further movement of the shaft 20 will transmit motion to the arm 31, which motion will be in turn transmitted through the connecting link 44 to the skylight member 15. The parts are so designed and constructed that the shoulders 34 will engage 60 the shoulders 33 at the same time the skylight 14 reaches its highest position, due to the alignment of the lever 30 with the connecting rod 41, as indicated by the dotted line

position 30'' of the said lever, so that any further counter-clockwise movement of this latter lever will begin to lower the said skylight 14. It thus results that from this point on, in the movement of the shaft 20, 70 the skylight 14 will be lowered, while the skylight 15 will be raised.

It will be noted that due to the positive connections between the skylight 14 and the shaft 20, that the said skylight is at all 75 times positively raised or lowered. On the other hand, due to the lost motion provided in the connections between the skylight 15 and the shaft 20, this skylight is positively raised, but will be lowered by the force of 80 gravity.

It will also be apparent that in view of the use of the force of gravity to lower the skylight 15, that the said skylight would not be lowered if the arm 31 should become 85 aligned with the connecting link 44, and in order to prevent this, the extreme end of the said arm 31 is provided with a lug 50, see Figs. 6 and 7, which is adapted to be engaged by the sides of the connecting link 44 when a certain predetermined point is 90 reached, to prevent further movement of the parts. It is thus necessary to reverse the direction of rotation of the shafts 20 and 23 in order to lower the skylight 15, which will 95 also have the effect of lowering the skylight 14 thereafter.

It will also be noted that the parts will be held in any adjusted position, due to the employment of the worm drive, since such a 100 drive is substantially irreversible and will efficiently lock the parts in any adjusted position.

While one form of the invention has been illustrated and described, it is obvious that 105 those skilled in the art may vary the details of construction as well as the arrangement of parts, without departing from the spirit of the invention, and therefore it is not wished to be limited to the above disclosure except as may be required by the 110 accompanying claims.

What is claimed is:

1. The combination with a pair of closures of a closure operating mechanism comprising a shaft; a positive connection between said shaft and one of said closures for opening and closing the same; a connection providing lost motion between said shaft and the other of said closures whereby it may 115 be opened and closed independently of said first named closure, and means for limiting the movement of one of said connections in one direction.

2. A device for operating a pair of skylights comprising a shaft; means for driving said shaft; a pair of arms carried by said shaft, one of them being rigid therewith; means carried by said shaft for permitting lost motion between the same and 125 130

the other of said arms; and connections between said arms and said skylights.

3. A device for operating a pair of skylights comprising a shaft; means for driving said shaft, said means being adapted to lock the parts against undesired reverse movement; a pair of arms carried by said shaft, one of them being rigid therewith; means carried by said shaft and cooperating with the other of said arms for permitting lost motion therebetween and connections between said arms and said skylights.

4. A device for operating a pair of skylights comprising a shaft; means for driving said shaft; an arm rigidly carried by said shaft; a second arm loosely mounted on said shaft; means carried by said shaft for transmitting motion therefrom to said second arm, said means permitting of lost motion between the parts; and connections between said arms and skylights.

5. A device for operating a pair of skylights comprising a shaft; a worm and worm wheel for driving said shaft; an arm rigidly carried by said shaft; a second arm loosely carried by said shaft, provided with a shoulder; a collar rigidly carried by said shaft, provided with a shoulder adapted to engage said first named shoulder to trans-

mit motion to said second arm, said shoulders being arranged to permit a predetermined amount of lost motion between the parts carrying the shoulders and connections between said arms and skylights.

6. A device for operating a pair of skylights comprising a shaft, means for driving said shaft, a pair of arms carried by said shaft, one of them being rigid therewith, the other of said arms being provided with a shoulder, and means carried by the shaft and adapted to cooperate with the shoulder to permit of lost motion between said arm and shaft, and connections between said arms and skylights.

7. A device for operating a pair of skylights comprising a shaft, means for driving said shaft, an arm rigidly carried by said shaft, a second arm loosely carried by said shaft provided with a shoulder, a collar rigidly carried by said shaft and adapted to engage said shoulder to transmit motion to the second arm, said shoulder and collar being arranged to permit a predetermined amount of lost motion between the said arm and shaft, and connections between said arms and skylights.

In testimony whereof, I affix my signature.

ANDERS H. NESHEIM.
